CLAIM

I claim the ornamental design for a mounting bracket, as substantially shown and described.

DESCRIPTION

FIG. 1. is an isometric view from above of a mounting bracket;

FIG. 2. is an isometric view from below thereof;

FIG. 3. is a left side view thereof;

FIG. 4. is a right side view thereof;

FIG. 5. is a rear view thereof;

FIG. 6. is a front view thereof;

FIG. 7. is a top view thereof; and,

FIG. 8. is a bottom view thereof.

The broken lines in the drawings depict portions of the mounting bracket that form no part of the claimed design.
